(57) **CLAIM**

I claim the ornamental design for a smoking article, as shown and described.

DESCRIPTION

FIG. 1 is a top perspective view of an alternative embodiment of a smoking article.

FIG. 2 is a bottom perspective view thereof.

FIG. 3 is a left side view thereof.

FIG. 4 is a front view thereof.

FIG. 5 is a right side view thereof.

FIG. 6 is a rear view thereof.

FIG. 7 is a top view thereof; and,

FIG. 8 is a bottom view thereof.

In the drawings, the broken lines shown in the figures depict unclaimed subject matter and form no part of the claimed design. The design is shown with symbolic break lines. The appearance of any portion of the article between the break lines forms no part of the claimed design.
